(57) **CLAIM**

The ornamental design for a display screen or portion thereof with graphical user interface, as shown and described.

DESCRIPTION

FIG. 1 is a perspective view of a display screen or portion thereof with graphical user interface in accordance with the present invention, shown in the environment of a tablet; FIG. 2 is a front view thereof;

FIG. 3 is a perspective view of a display screen or portion thereof with graphical user interface in accordance with the present invention, shown in the environment of a monitor; and,

FIG. 4 is a front view thereof.

The broken line showing of a display screen with graphical user interface is included for the purpose of illustrating portions of the article and forms no part of the claimed design. The broken line showing of a tablet and monitor is included for the purpose of illustrating environmental structure and forms no part of the claimed design.

1 Claim, 4 Drawing Sheets
